UNITED STATES PATENT OFFICE.

RALPH SWAN CLARKE, OF WALPOLE, MASSACHUSETTS, ASSIGNOR TO BIRD MACHINE COMPANY, A CORPORATION OF MASSACHUSETTS.

APPARATUS FOR PRODUCING AND FEEDING PAPER PULP.

Application filed October 12, 1922. Serial No. 594,076.

This invention pertains to an improved method of and apparatus for the production and feeding of paper pulp to paper making machines, and has for its main object the

5 provisions of means whereby a large amount or volume of water, much in excess of that employed with any installation of which I am aware, may be utilized in a screen for cleaning the pulp, and the surplus water 10 extracted from the pulp to reduce the same to the desired consistency after it leaves the screen and prior to its being fed or passed to the paper making machine proper.

In the continuous manufacture of paper 15 of uniform grade, it is essential that the stock or pulp be clean, and this cleaning may be accomplished by various means, as, for instance, in screens of the rotary type, such as are depicted in U. S. Letters Patent 1,210,906, R. D. Clarke, dated January 2, 1917, and 1,304,253, Charles S. Bird, dated May 20, 1919. The invention hereinafter 20 set forth and claimed is shown in connection with such a screen, that is to say, a screen 25 of the rotary type, and reference is made to the aforesaid patents for a detailed description of such a screen.

The apparatus here involved may be said 30 to comprise a screen of the rotary type, from which the pulp with an excess of water therein, is discharged into a vat or receptacle in which a dewatering means is employed, in this instance, a rotary screen, and from which vat or receptacle the dewatered 35 pulp, or the pulp reduced to the proper consistency, is discharged or passes into the head box of a paper-making machine.

One embodiment of the invention is 40 shown in the accompanying drawings, wherein,—

Fig. 1 is a vertical longitudinal sectional view of the apparatus;

Fig. 2 an enlarged end elevation of the 45 dewatering vat showing the discharge opening leading from the dewatering device or screen;

Fig. 3 a vertical sectional view of the 50 dewatering screen at the discharge end thereof, the section being taken on the line III—III 55 of Fig. 4;

Fig. 4 a top plan view of the dewatering 60 screen and the vat in which it works, and the head box;

Fig. 5 a transverse vertical sectional view taken on the line V—V of Fig. 4; and

55

Fig. 6 a detail sectional view of the discharge end of the dewatering screen.

Referring to said drawings, 1 denotes the 60 rotary pulp screen mounted to rotate within a vat 2, the screen being submerged throughout the major portion thereof. An oscillating or shaking motion is imparted to the vat to cause a surge of the pulp in the vat with reference to screen to cause the pulp to pass inwardly into the screen, all 65 in a manner as set forth in the patents above specified. The usual shower pipes and water collecting troughs are shown, but form no part of the present invention.

The discharge mouth of the cleaning 70 screen 1, which mouth is denoted by 3, stands adjacent one side of a trough 4, the mouth being partially cut off from the trough by dam boards 5 which control the flow of the cleaned pulp with the excess of 75 water therein into the trough, and likewise control the correct level of the pulp in the cleaning screen and its vat. At the opposite side of the trough 4 there is located a 80 dam or weir 6, adjustable as to height, and over which the dewatered pulp, or the pulp 85 which is reduced to the proper consistency, flows into the head box 7 of a paper-making machine, whence it passes, in the usual way, to a paper-making machine of any approved type.

In Fig. 1 there is indicated a roll 8 of the 90 paper making machine, in order that the relationship of the various portions of the apparatus may be clearly understood.

Located adjacent the intake end of the trough 4, or adjacent the dam 5, is a baffle board 9 which extends entirely across the trough from end to end, and from the top to a point adjacent the bottom of the trough, 95 so as to produce a passage 9^a between the lower end of the baffle and the bottom of the trough, whereby the pulp as it passes from the cleaning screen, will be distributed and deflected into the bottom of the trough, 100 thus preventing a direct current through the trough and an accumulation of dead stock therein.

Mounted in the upper portion of the trough 4 is a dewatering or filtering element, 105 which, in the instant case, takes the form of

a rotary screen closed at one end and open at the other, and into which the excess water drains owing to the slight pressure which obtains upon the lower portion of the screen 5 due to the submergence of the screen in the pulp. Mounted in suitable bearings at the ends of the trough 4 is a shaft 10, upon which is secured a series of spiders or open wheel-like elements 11, to the periphery of 10 which there is attached a sheet of perforate metal 12 having relatively large openings 13 formed therein. This forms a drum-like element upon which is imposed a wrapping of wire cloth 14, having a relatively open mesh, 15 say #14, and upon this there is laid an outer covering of finer mesh wire cloth 15, say about #20 mesh.

One end of the rotary screen thus formed is closed by a head 16 (Fig. 4). The opposite end is open and stands adjacent to an arcuate shaped member 17, L-shape in cross section, and secured to the inner face of the end wall of the trough. A discharge opening 18 stands in line with the lower portion 25 of the screen so that any water passing into the screen will be discharged freely therefrom. In order to prevent the pulp from passing into the open end of the screen, I employ means coacting with the outer spider 30 or member 11 and the arcuate member 17, which, in the present instance, takes the form of a band 19 fixed at one end on a pin 20 secured in a bracket 21 attached to the upper edge of the wall of the trough 4, the band 35 being provided with a liner or facing 22 of suitable material which takes against the outer face of the curved or arcuate member 17 and the outer face of the member 11. Proper tension is maintained upon the band 40 by means of a threaded extension or arm 23 which passes freely through an eye formed in a post 24 mounted in a fixed bracket 25. A wing nut 26 threaded upon the upper end of the arm 23 admits of proper adjustment 45 of the band, and, consequently its liner 22, against the face of the fixed member 17 and the outer face of the adjacent spider member 11. Clean out openings 27 are preferably provided at each end of the trough 4 in 50 order that the trough may be cleaned out from time to time, as occasion may require.

A shower pipe 28 will be provided for the rotary dewatering screen, and while I have shown this pipe as being located exteriorly thereof, it may be located interiorly 55 provided a screen of the type shown in connection with the cleaning screen be substituted for that above described.

In operation, the pulp to be cleaned and fed to the paper-making machine is passed to the vat 2 along with an excess of water, or an excess of water may be supplied to the screen independently of the pulp, and is 60 therein treated and separated in the usual manner, as obtains with screens of this type.

The cleaned pulp with an excess of water passes over the dam 5 into the trough 4 and beneath the baffle 9 to a point below the screen, the baffle tending to properly distribute the pulp throughout the length of 70 the trough so that the pulp will pass alike to all portions of the dewatering screen. The dewatering screen, as above noted, is rotated and the excess water in the pulp passes through the screen surface to the interior of 75 the screen, thence out through the open end where it is discharged through the opening 18. The pulp thus thickened finally flows over the weir 6 into the head box 7 and thence to the paper making machine proper. 80

As before noted, to secure the maximum efficiency of the rotary pulp cleaning screen 1, it is necessary to maintain the correct level of the pulp in the vat. This, as also indicated above, is brought about by the use 85 of the dam 5. It may, however, be desirable to run a lower level in the trough 4 where the thickener or dewatering screen is placed. This is allowed of by varying the height of the weir or dam 6. It is manifest 90 that in so far as the broad invention is concerned, a dewatering element of a construction other than that above set forth and described may be employed, and in so far as the generic invention is concerned, I do not desire to be limited either in the employment 95 of a particular form of cleaning screen or a particular form of dewatering device.

What is claimed is,—

1. In an apparatus for cleaning paper 100 pulp and feeding the same to a paper-making machine, the combination of a vat; a rotary screen located in the vat and adapted to be partially submerged in the paper stock fed to the vat, said screen being open at one 105 end for the discharge of the cleaned pulp which passes inwardly into the same; a trough located adjacent the discharge end of the screen; a dam controlling the outflow of the cleaned pulp from the screen into the 110 vat; a dewatering device located in the upper portion of the trough; and a weir located at the discharge end of the trough, over which the thickened pulp may flow.

2. In an apparatus for cleaning paper 115 pulp and feeding the same to a paper making machine, the combination of a vat; a screen mounted within the vat and adapted to be partially submerged in the paper stock placed within the vat, one end of the screen being open, and through which the cleaned pulp which passes inwardly into the screen from the vat is discharged; a trough located adjacent the discharge end of the screen; means for regulating the level of the stock 120 within the vat and controlling its discharge into the trough; a rotatable cylinder placed in the upper portion of the trough, said cylinder being provided with a filtering surface 125 which permits the passage of water inward. 130

ly into the screen, one end of the screen being open to admit of the discharge of water which passes into the same; and an adjustable weir located at the discharge side of 5 the trough and over which the pulp, from which the water has been partially extracted, may pass.

3. In an apparatus for cleaning paper pulp and feeding the same to a paper-making machine, the combination of a vat; a rotary screen located therein, one end of the screen being open; a trough located adjacent said open end and adapted to receive the cleaned pulp from the cylinder; a dam controlling the level of the stock in the vat and its discharge from the mouth of the screen into the vat; a baffle mounted in the trough adjacent said dam, said baffle causing a downflow of the pulp beneath its lower edge, 10 and a consequent distribution of the pulp throughout the length of the trough; a rotary drum-like member mounted in the upper portion of the trough; a filtering surface carried upon said drum-like member; an 15 adjustable weir located at the discharge side of the trough and over which the pulp, from

which the water has been partially withdrawn by said rotary drum-like member, may pass to the paper-making machine.

4. In an apparatus for cleaning paper pulp and feeding the same to a paper-making machine, the combination of means for 20 cleaning pulp in the presence of an excess of water; a trough into which said pulp is discharged along with said excess of water; a 25 rotary drum-like member located in the upper portion of the trough, said trough being provided at one end with a discharge opening in line with the lower portion of the drum-like member; an arcuate member 30 secured to the inner face of the end of the trough and extending below and upwardly from each side of the opening; and means for effecting a tight joint between said member and the end of the drum-like member 35 to prevent ingress of water or pulp into said open end of the screen while still admitting of free rotation of the drum-like member.

In testimony whereof I have signed my 40 name to this specification.

RALPH SWAN CLARKE.
